CLAIM

The ornamental design for a pod for indoor plant cultivator as shown and described.

DESCRIPTION

FIG. 1 is a front perspective view of a pod for indoor plant cultivator showing our new design;

FIG. 2 is a front view thereof where the back view is a mirror image;

FIG. 3 is a left side view thereof where the right side view is a mirror image;

FIG. 4 is a top plan view thereof;

FIG. 5 is a bottom plan view thereof;

FIG. 6 is a bottom perspective view thereof;

FIG. 7 is an exploded view thereof with additional environmental structure;

FIG. 8 is an exploded view showing the pod for indoor plant cultivator within a broken line environment of use;

FIG. 9 is an enlarged view of portion 9 shown in FIG. 1; and, FIG. 10 is an enlarged view of portion 10 shown in FIG. 4. The broken line showing of two rectangular covers and ten rectangular pillars in FIG. 7 and the broken line showing of a tray, shelf, and indoor plant cultivator in FIG. 8 are for the purpose of illustrating environmental structure and form no part of the claimed design. The dash-dot broken lines define the bounds of the claimed design and form no part thereof. The dash-dot-dot broken lines represent the boundaries of the enlarged portions and form no part of the claimed design.
